UNITED STATES PATENT OFFICE

CARLETON HUNNEMAN, JR., OF BROOKLINE, MASSACHUSETTS

DRIER

Application filed May 14, 1928. Serial No. 277,411.

The principal object of my invention is to provide a simple, compact and inexpensive device that is particularly adapted for the drying of clothes or other articles and especially by the occupants of apartments.

5 A feature of my invention is a plurality of pivoted arms or spreaders mounted to lie parallel with each other in a horizontal plane when in closed position.

10 Another feature is a particular arrangement for off-setting the arms with relation to a common pivot so that the arms may be parallel when in closed position.

15 Another feature is a particular location of knots in the supporting ropes or cords to hold the latter taut when the device is in use.

Other features will be pointed out below:

In the drawing—

20 Figure 1 is a plan of a device embodying my invention;

Figure 2 is a front elevation thereof;

25 Figure 3 is a plan of the same, but on a smaller scale, and with the arms in open or extended position;

Figure 4 is a right end elevation; and

Figure 5 is a partial section, enlarged, on line 5—5 of Figure 2.

30 My device is preferably located so as to be accessible from window 1 in the wall 2 of a building and is mounted on bracket 3 held to wall 2 by screws 4, the bracket having perforated lugs 5 and 6 to receive the pivot rod 7.

35 I provide a plurality of arms or spreaders 8, 9, 10 and 11, preferably of spruce or some equally tough and flexible material, each being suitably perforated at intervals for passage of the ropes or cords described below.

40 Arm 8 has fixed to it a connecting member, preferably of metal, and having a portion 12. Integral with portion 12, but at right angles to it, are lugs 13 and 14, spaced apart and perforated to receive pivot rod 7. This construction offsets arm 8 from rod 7, that is,

45 the arm 8 is not radial with reference to the pivot rod 7. Arm 11 has a similar connecting member 15 but the lugs of the latter are spaced slightly less apart than the lugs 13 and 14 and are located between lugs 13 and

14. (See Figure 4.) Similarly, arm 9 has lugs which are shorter than lugs 13 and 14 and are located between the lugs of arm 11. Similarly, arm 10 has short lugs which are located between the lugs of arm 9. This off-setting of the arms permits them to lie parallel in a horizontal plane when in closed position.

55 Fixed to arm 8 is a supporting member 16 which is preferably a flat metal strip, bent at a right angle near its top and there perforated to receive the pivot rod 7. Similar supporting members 17, 18 and 19 are provided for the other arms. A cotter pin 20 may be inserted in the pivot rod below member 16 and a cotter pin 21 may be similarly inserted above member 19 to keep the supporting members in place axially of the pivot rod, the supporting members being free to swing on the pivot rod 7. A cotter pin 22 may be inserted in the pivot rod 7 just above lug 6 to prevent the pivot rod from dropping enough to permit its upper end from becoming free of lug 5. A cotter pin 22' is preferably applied to the pivot rod just above the lug 13.

60 Connecting arms 8 and 9 is a locking hinge 23 of the stepladder type and this is slightly bowed as shown to give a slight toggle effect to ensure holding in the locked position. Similar locking hinges 24 and 25 are provided for the other arms.

65 A clothesline 26, or other suitable line, is knotted at 27 and then passes through a perforation in arm 11 and extends to arm 10 where it is knotted at 28, then passing through a perforation in arm 10 and being knotted at 29 and extending similarly, as shown, through arms 9 and 8 and being knotted at 30, 31 and 32. The purpose of the 70 knots is to hold the line taut when the arms are spread and while I might hold the stretch of line between any two adjacent arms taut by means of two knots, such as 27 and 29, because they engage sides of the arms 11 and 10 which are remote from each other, yet for some purposes I prefer to use also the additional knot such as 28.

75 Additional lines, such as 33 and 34, similarly knotted, may be provided as desired.

100

A hook 35 fastened to arm 11 cooperates with eye 36 on arm 8 to hold the arms parallel to each other when in closed position. A suitable hook 37 may be attached to the building to engage an eye on arm 11 to hold the device against swinging when in its closed position.

A holding hook 38 may be attached to the building and may engage either of the eyes 39 or 40, depending on whether the device is used from the right or the left. The hook 38 holds arm 11 and consequently arm 8 against swinging when in open position and also holds said arms properly spaced from the building or other support to prevent possible contact between the clothes and support.

The bracket 3 having been attached to some suitable support, for example adjacent to a window on the wall of a dwelling, the upper end of the pivot rod 7 is passed up through the perforation in the upper lug 5 of the bracket until the lower end of the pivot rod clears the lower lug of the bracket. The lower end of the pivot rod may then be brought in and lowered into the perforation in the lower lug of the bracket and brought to rest, the cotter pin 22 in the pivot rod just below the point where the arms are attached to it preventing its dropping enough to bring the upper end of the pivot rod below lug 5. The drier is now supported in the bracket yet is free to swing sideways. The clamp hook 35 is unhooked from its eye permitting the arms to swing apart. The hinge 23 is next opened, and locked in position, holding arm 8 at a predetermined distance from arm 9 and stretching the strands of clothesline between arms 8 and 9. The knot 30 prevents the slack line between the unopened succeeding sections of the device slipping through arm 9 which might cause the line between arms 8 and 9 to fall slack. The clothes are now placed on the lines between arms 8 and 9 and then hinge 24 between arms 9 and 10 is opened, pushing out arm 9 and stretching the lines between arms 9 and 10. This operation makes the lines between arms 9 and 10 available for use, in the same manner as those between arms 8 and 9 were made available. The operation is repeated a third time with hinge 25 making the lines between arms 10 and 11 available. The device is now fully opened and is comparatively rigid except for the fact that it is still free to swing sideways. To prevent this occurrence a hook which has been attached to the wall or window sill is hooked into a co-operating eye on arm 11.

To take in the clothes and fold the drier and remove it from its bracket for storage within the building, the above described steps are reversed.

The device is so simple in design that it is economical of manufacture and may be operated by anyone of moderate intelligence. It is light in weight and therefore adaptable

to use by women who are almost exclusively the users of such an article. It has no loose parts or pieces to be handled in operating it, or to be mislaid. It may be placed in, or removed from its bracket by a single simple operation. When folded and stored, it occupies little space and, since it is so easily removable from outside, it can be protected from the weather, within the house, when not in use. It is primarily intended for use by the occupants of apartments who otherwise have to go up or down stairs either to the roof of the building or to the yard, or more especially for those who live in congested districts where neither roof nor yard are available, to obtain outdoor drying of their clothes, since the washing may be put on the device without the tenant leaving his or her apartment. The device may be attached to a building at any height since it does not depend for support on anything except the object to which the bracket is fastened and that in which the eye of the holding hook is screwed. If desired, it may be attached to a post, fence, or similar object near the ground and operated from the latter.

The ease of operation of the device and its freedom from becoming out of order are the result of a design which provides no point where wood works upon wood and might, therefore, bind because of exposure to dampness, and which incorporates no pulleys or points through which the line works which might cause it to bind or become abraded. The line is held in the arms at the same point irrespective of whether the device is open or folded because of the knots that are tied in it. There are no lines to adjust when using the device. In fact it is unnecessary to handle them at all except for the customary operation of putting the clothes on them. Snow and ice have little or no effect on the operation of the drier, as through every point which might be affected by their accumulation there is a powerful leverage so that the user could dislodge either with slight effort. In inclement weather when the ground is uncomfortable underfoot it has distinct advantages over driers that require their users to stand upon the ground. Except when it is obviously necessary, in putting clothes on, or removing them from, the drier, there is no need of having the window at all open, irrespective of the position of the device (i. e. open or closed).

My device minimizes the possibility of the clothes coming in contact with the metal work of the device which, even if finished with a non-rusting surface, might soil them. The likelihood of the clothes being blown against the wall is small since those nearest it are at a considerable angle to the latter, rather than parallel, and by the design of the drier being such that when fully extended and hooked, it becomes comparatively rigid in place pre-

- venting its being swung about against the wall or tossed up and down by heavy gusts of wind. The lines being parallel and adequately spaced throughout their entire length, 5 the clothes are subject to a sufficient circulation of air to dry them quickly and are unlikely to come in contact with one another. When an opened section has been filled with clothes and is being swung out so that the 10 succeeding one may be opened and filled, the relative positions of its arms do not change, thereby keeping its lines equally and fully stretched, as some of the clothes might be unduly blown about if one or more of the lines 15 fell slack. Adequate clothesline is provided, yet it is accessible from a single window because of the peculiar design of the drier which permits one section to be fully opened with its lines equally and fully stretched and loaded 20 with washing while the succeeding sections are still unopened. The shrinkage of the clothesline which may occur if the drier is carelessly exposed to rain is taken care of by the flexibility of the arms.
- 25 The size, shape, and style of the door or window adjacent to which the drier may be attached is of no consequence, it being assumed that any kitchen, bedroom, or other window that the user might select would be 30 at least of the smallest size that general practice provides for such a room. It is unnecessary to cut, bore through, or in any way injure or modify the sash, frame, casing or sill in installing the device with the exception of 35 screwing the eye of the holding hook into the sill, and this is optional with the user as it may be attached to the wall below it. The holding hook is of such length that it will fit any ordinary condition and in cases where it 40 is too long to extend out at right angles to the wall, its eye may be so placed that the hook extends out from the building to the arm diagonally.
- 45 When used from a window or door, the drier may be placed either to the right or to the left without affecting its operation, as it opens or folds from either end.
- 50 Because of its peculiar hinge construction the arms lie parallel and in the same horizontal plane when folded, although all swing on a common pivot, providing a small space between each two to allow room for the knots and slack line, and making for a more compact device than would be possible did the 55 arms radiate from a common center.
- 55 The invention is not confined to that illustrated in the accompanying drawing as the number of arms and lines, and their length, and other dimensions, might be varied considerably, and minor changes might be made in the construction, without departing from its principle.
- 60 What I claim is:
- 65 1. A device of the character described comprising a plurality of at least three independently-movable arms pivoted on a common vertical pivot, said arms being parallel in a horizontal plane when in closed position; a line between, and connected to, adjacent arms; and means to hold said arms properly spaced from each other when in open position to keep said line substantially taut even when the other arm or arms are in folded position. 70
2. A device of the character described comprising two independently-movable arms pivoted on a common vertical pivot, at least one of said arms being offset with relation to said pivot, said arms being parallel in a horizontal plane when in closed position; a line between, and connected to, said arms; and means to hold said arms properly spaced from each other when in open position to keep said line substantially taut. 75
3. A device of the character described comprising a plurality of at least three independently-movable pivoted arms, said arms being parallel in a horizontal plane when in closed position; a line extending from each arm to the adjacent arm; and means to hold desired adjacent arms in open position with the line between them taut even when the other arm or arms are in folded position. 80
4. A device of the character described comprising a plurality of at least three arms mounted to swing horizontally on a fixed common pivot; a plurality of elements for supporting clothes and extending from one arm to the adjacent arm, said elements being parallel when the device is open; and means to hold the arms in open position. 85
5. A device of the character described comprising a plurality of at least three arms; a support for said arms upon which said arms are mounted to swing horizontally; means carried by the arms for supporting clothes; and means to hold desired adjacent arms properly spaced away from said support when in open position even if the remainder of said plurality may be in folded position. 90
